DESIGN FOR A DRESS ENSEMBLE

Dorothy High, New York, N. Y.

Application April 17, 1937, Serial No. 68,831

Term of patent 3½ years

To all whom it may concern:

Be it known that I, Dorothy High, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a fragmentary view of the rear portion of the dress unit of the dress ensemble.

The rear portions of the coat and dress units of the instant ensemble are conventional.

The dominant feature of my design resides in the specific configurations of the gores on the front of the coat and dress units as shown, said gores terminating above the waistline in the manner disclosed.

I claim:

The ornamental design for a dress ensemble, substantially as shown and described.

DOROTHY HIGH.
